NILS E. LINDENBLAD, OF PORT JEFFERSON, NEW YORK, ASSIGNOR TO RADIO CORPORATION OF AMERICA, A CORPORATION OF DELAWARE

MEANS FOR ENERGIZING ANTENNAE

Application filed May 22, 1929. Serial No. 365,024.

This invention relates to feeders or lead-in structures for antennæ and has for one of its objects the provision of new and useful methods and means for energizing antennæ.

In my copending United States patent application Serial #304,445 filed September 7, 1928, on antennæ, I have shown how, by the use of a pair of linear radiators a certain number of half wave lengths long radiation in four directions may be obtained; by the staggering of the arrangement referred to I have shown how radiation is made predominantly bidirectional; and, by the use of staggered pairs of the bidirectional arrangement, I have shown how unidirectional radiation may be obtained. Those structures have, for supplying energy thereto, feeders which have certain portions run relatively close together and parallel, and other portions which diverge in order to supply energy to the radiators.

I have found that where the antenna feeders or lead-ins were run close together and substantially parallel, because of the substantially concentric fields about the leads there is radiation cancellation and hence those portions do not affect the radiational directivity of the antenna. On the other hand where the feeders diverge the fields thereabout are no longer concentric, they no longer cancel but tend to set up large radiation components which militate against accurate directional radiation. Accordingly another and more specific object of this invention is to provide a method and means whereby radiation from the diverging portions of feeders or lead-in structures is substantially eliminated or lessened to such a degree that it has no appreciable militating effect.

Still another object of this invention is to provide an additional arrangement of supply feeders for antennæ, of the character referred to, in which diverging portions are dispensed with.

It is to be understood, of course, that while this invention is peculiarly adapted for antennæ of the character described in my copending application referred to above, it is not limited in use thereto, but, the principals

of my invention may be applied to any radiating system.

The invention may most readily be understood by referring to the accompanying drawing in which

Figure 1 illustrates a manner in which radiation cancellation from the diverging portions of feeders is obtained by providing additional lead-in structure;

Figure 2 is an embodiment wherein radiation is reduced from the diverging portions of the feeder structure by looping the same; and

Figure 3 shows a manner in which diverging feeders may be dispensed with.

Referring to Figure 1 numeral 1 indicates a transmitter supplying, over the relatively close parallel portions 3, 5 of feeders and diverging portions 7, 9, energy to radiators 11, 13. Radiators 11, 13 are excited, as disclosed in my copending application referred to hereinbefore, in phase opposition; hence, because of the close contiguity of portions 3, 5 and because of the substantial concentricity of the fields thereabout, there will be substantially no radiation therefrom.

However, there is no radiation cancellation of portion 7 by portion 9 or the reverse because those portions do not have substantially concentric fields. In order, therefore, to cancel radiation from those portions I run additional leads or feeders from point 15 to point 17 substantially parallel to and close to portion 7 and a lead parallel to portion 9 from point 19 on lead 5 to point 21.

It will, therefore, be clear that because of the free electrical ends 17 and 21, standing waves will be produced on the leads or wires 17, 15 and 19, 21. By suitably choosing the lengths of these wires the standing waves on them may be made to exist in phase opposition to the standing waves caused on portions 7, 9 due to reflection from points 23, 25. In this manner, as portions 7 and 9 will have substantially concentric and opposing fields thereabout radiation from diverging portions 7 and 9 will be practically eliminated.

Of course, it may be impossible to have points 17 and 21, in order to have phase op-

position with the diverging portions of the feeders or lead-ins, exactly opposite the extreme ends of portions 7 and 9. However, it will be found that points 17 and 21 will be sufficiently opposite to the extreme ends of the diverging portions of the antenna feeders so that sufficient radiation cancellation is obtained.

In Figure 2 reduction of radiation along 10 the diverging portions 70, 90 is obtained by placing loops in, or folding up the diverging portions. The loops 72 may or may not be in the same plane.

The reason why radiation from the diverging portions in this case is reduced, may be explained as follows. If the diverging portions were straight, the standing waves thereon caused by reflection from points 25 and 23 would have points of average maximum potential relatively far apart. Accordingly, the paths that electrostatic flux would take in travelling between these points would be large and radiation would be sufficiently great to lessen the desired directive characteristics of the antenna. By folding up the diverging portions, the distances between points of average maximum potential is reduced, and accordingly, the lengths of the paths of electrostatic flux are reduced resulting in greatly decreased radiation from the diverging portions 70, 90. This looping is to be considered, therefore, as lessening the radiation resistance of the portions 70, 90.

In Figure 3 I have shown a manner in 35 which diverging portions for energizing antennæ of the general character described are eliminated. For the sake of example, I have indicated four staggered radiators 30, 40, 50, 60. For radiation in the direction of the 40 arrow the standing waves on these wires, as disclosed in my copending application, should have phase relationships so that considering the standing wave on radiator 40 as a reference point, the wave on 30 45 should be 90 degrees therefrom, the wave 50 should be 270 degrees therefrom and the wave on 60 should be 180 degrees therefrom.

By the use of parallel paths or feeders 50 such as 32, 34; 42, 44; 52, 54; 62, 64, connected between transmitter 1 and radiators 30, 40, 50, 60, standing waves may be produced on the radiators. The paths should be connected to the radiators intermediate their 55 ends; and, the portions included between, say, points 36, 38, should be equal to the characteristic impedance of, for example, the lead-ins 32, 34. And similarly, for example, the impedance between points 66, 68, should 60 be equal to the characteristic impedance of lines 62, 64.

Because of the close propinquity and parallel paths of the lead-ins, or feeders, for example, 32, 34, radiation therefrom is substantially eliminated.

Having thus described my invention, what I claim is:

1. In combination, a pair of radiators, a pair of diverging feeders for supplying energy thereto, and leads run from each 70 feeder close to and parallel to the other feeder.

2. In combination a pair of radiators, a pair of diverging feeders for supplying energy thereto and leads having free electrical ends run from each feeder close to and 75 parallel to the other feeder.

3. In an antenna comprising radiators having diverging feeders for supplying energy thereto, a lead connected to one feeder running parallel and contiguous to another feeder for cancellation of radiation therefrom.

4. In an antenna comprising a pair of linear radiators excited in phase opposition 80 having diverging feeders for supplying energy thereto, leads, cross connected to the energy supply feeders running parallel and in close proximity to the radiator supply feeders, said parallel run leads having free 85 electrical ends.

5. An antenna having a plurality of radiators, diverging feeders therefor, and a lead, 90 from each feeder taken at a point where the feeders begin to diverge to feed the individual radiators of the antenna, running parallel and close to a feeder other than the one to which it is connected.

6. In an antenna comprising a pair of radiators having diverging feeders for supplying 100 energy thereto, a lead connected to one feeder running parallel and close to the other feeder for cancellation of radiation therefrom.
